JOURNAL BOX LUBRICATOR

Chen Ming Chih, Park Forest, Ill., and John K. Backus, Tonawanda, N.Y., assignors to General Mills, Inc., a corporation of Delaware

Filed Aug. 1, 1957, Ser. No. 675,660

5 Claims. (Cl. 308—87)

This invention relates to lubricating devices for shafts, axle journals and the like, and particularly to improved lubricators which, by means of capillary action, convey liquid lubricants from a reservoir to a rotating journal such as that used on railway rolling stock equipped with solid journal bearings.

Whereas various devices such as felt pads, textile waste, natural sponges, synthetic sponges, rubber sponges and the like have been previously employed in railway journal boxes for transmitting oil from the bottom of the journal box up to the rotating axle or journal, such devices of the prior art have been found to provide less than the desired results because of certain inherent disadvantages associated with the use of such materials. For example, it has been determined by experience that waste packings for journal boxes are inefficient because of the difficulty of proper installation and the need for continual agitation to keep the waste in contact with the journal, and because this material is a relatively slow transmitter of lubricant from the journal box reservoir to the rotating journal. Furthermore, waste packing tends to glaze and surface harden and is subject to what is known as "waste grab" which occurs when the waste fibers are caught by imperfections in the journal surface and are carried between the journal and the surface of the bearing. Moreover, such packings shift positionally incidental to train start ups. Packings formed of other materials hereinabove may also possess some or all of the recited disadvantages, and in addition usually tend to settle or compress incidental to use, and require relatively large supplies of reservoir oil to insure continued functioning.

One object of the invention is to provide a lubricator of the synthetic cellulose sponge variety that will effectively bear upon the underside of a car journal and thereby provide a dependable and uniform lubrication thereof. More specifically, it is an aim of the invention to augment to a desired degree the pressural action of the sponge so as to enhance its lubrication capability. Further, it is within the purview of the invention in one specific instance to permit a compression of the sponge in an interior region thereof rather than at its lubricating face, thereby permitting relatively free passage of the lubricant from the sponge to the bearing surface of the journal as said journal rotates.

Another object is to provide a lubricant requiring no agitation or handling after having once been installed and only slight additions of lubricant over long periods of time.

Still another object of the invention is to provide a packing medium formed of non-fibrous, non-linting material thereby eliminating fiber grab between the journal and the bearing.

Other objects of this invention will become apparent in the following description and from the accompanying drawings which form a part of the specification.

FIGURE 1 is a longitudinal sectional view through a railway car journal box, showing a lubricating pad of the present invention installed therein;

FIG. 2 is a fragmentary sectional view of the invention taken on line II—II of FIG. 1;

FIG. 3 is a perspective view of one of the lubricating pads removed from the journal box;

FIG. 4 is a plan view of a modified form of pad on a slightly reduced scale;

FIG. 5 is a sectional view of the form of FIG. 4 taken on line V—V thereof;

FIG. 6 is a view corresponding to FIG. 5 but showing another modification of the invention.

As shown in FIGS. 1 and 2 of the accompanying drawings a sponge block or pad 10, made preferably in two pieces 11 and 12, is made of synthetic cellulose material and mounted within the journal box 13 and below the journal 14 of the railroad car. In its preferred form, the cellulose pad constituting the journal box packing possesses a fiber structure such that the pores thereof have their major dimension extending in a generally horizontal direction. Such a pore orientation facilitates the insertion of the pad into the journal box. Also, this particular pore arrangement lessens somewhat the pressure of the pad against the journal during operation.

Each of the pads is formed with a number of horizontal apertures 16 located near the center thereof to provide a path for rapid transfer of liquid lubricant 20 along the length of the journal box. The provision of the apertures also equalizes and moderates the resilient force of the compressed pad against the journal, thus providing cooler operation. In other words, the apertures 16 are designed to make the pad compress more in the region of the apertures rather than at the surface which bears against the journal 14. In this way, relatively free passage of the lubricant occurs in the region where it is most needed, that is, where the sponge material actually engages the journal. The lubricating pads have a cross sectional shape substantially the same as the interior contour of the journal box and of the journal, and when put in position they are forced within the box and under the journal thereby being slightly compressed so as to snugly fit the journal box and the journal and thereby have little tendency to shift or roll when in use. The pad will, of course, become saturated with the lubricant disposed in the oil reservoir of the journal box by means of the capillary or wicking action of the material, whereby a continued supply of oil will be furnished to the axle.

The lubricating pad illustrated in FIGS. 4 and 5 is formed with horizontal apertures 16 and also with a series of vertical apertures 21 which extend through the pad from the top to the bottom thereof and open into the oil reservoir. Vertical motion of the journal as in moving railway cars periodically compresses the lubricating pad so that liquid lubricant is literally pumped to the journal through the vertical apertures. The vertical apertures 21 also provide a means of washing dirt to the bottom of the journal box, thereby preventing the dirt from filtering out on the contact surface with a resulting hardening of that surface.

The pad 32 shown in FIG. 9 is generally similar to that shown in FIG. 3 except that it is thicker through its central portion and the upper surface 33 thereof is struck from a radius larger than the radius of the journal, whereby when conformed to the journal greater pressure will be brought to bear on the central portion thereof. This form is preferably provided with longitudinal apertures 16.

As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

What is claimed:

1. In combination with a journal box and a rotatable journal extending thereto, a journal box lubricator comprising a pad of synthetic cellulose sponge material of a size to occupy substantially the entire space between the bottom of the journal box and the underside of said journal with substantially the entire lower surface of said pad engaging the bottom of said journal box and the upper surface of said pad being formed with an arcuate groove extending parallel to said journal and bearing thereagainst throughout the length and width of said groove, said pad also having a centrally disposed aperture extending therethrough in a direction substantially parallel to said groove and journal and spaced from both the upper and lower surfaces of said pad at an intermediate elevation such that its lower half is disposed beneath the level of the oil contained in the journal box.

2. A journal box lubricator in accordance with claim 1 in which the pore structure of the cellulose pad is oriented in such a direction as to have the major dimension thereof extend substantially horizontally when the pad is installed in a journal box.

3. A journal box lubricator in accordance with claim 1 in which said pad is thicker through its central portion.

4. A journal box lubricator in accordance with claim 1 in which said pad is also provided with an additional aperture spaced to either side of said first-mentioned aperture, said first-mentioned aperture being larger in cross-section than said additional apertures.

5. A journal box lubricator in accordance with claim 4 in which said pad is further provided with other apertures extending therethrough at substantially right angles to said first-mentioned aperture, said other apertures being disposed in groups between said first-mentioned aperture and said additional apertures.
